No. 708,050.

Patented Sept. 2, 1902.

F. J. KEIS.

MILK DIPPER.

(Application filed Oct. 26, 1901.)

(No Model.)

UNITED STATES PATENT OFFICE.

FRANCIS JAMES KEIS, OF WATERVLIET, NEW YORK.

MILK-DIPPER.

SPECIFICATION forming part of Letters Patent No. 708,050, dated September 2, 1902.

Application filed October 26, 1901. Serial No. 80,133. (No model.)

To all whom it may concern:

Be it known that I, FRANCIS JAMES KEIS, a citizen of the United States, residing at Watervliet, in the county of Albany and State of New York, have invented a new and useful Improvement in Milk-Dippers, of which the following is a specification.

This invention relates generally to milk-dippers, and more particularly to one having a spring-actuated cover which is normally closed.

Milk-dippers as ordinarily constructed comprise a cup and a long handle, by means of which milk is dipped up from the can and poured into the bottle or measure. Cups as a rule are quite large and cannot be filled to their limit, for the reason that in removing the dipper from the can and emptying the same it frequently happens that considerable quantity of the milk is spilled. For this reason the dippers are never employed for measuring a quantity of milk.

The object of my invention is to overcome this objection and provide a dipper which can be employed as a measure and which can be filled to its full capacity and carried about without spilling any of the contents.

The invention consists in certain details of construction and novelties of combination, all of which will be fully described hereinafter and pointed out in the claims.

In the drawings forming part of this specification, Figure 1 is a perspective view showing a milk-dipper constructed in accordance with my invention. Fig. 2 is a detail sectional view. Fig. 3 is a sectional view illustrating the top portion of the can and the manner of hinging the cover. Fig. 4 is a sectional top plan. Fig. 5 is a perspective view illustrating a detail of construction. Fig. 6 is a detail perspective view illustrating the lower portion of the handle.

In carrying out my invention I employ a cup or dipper A, having a long handle B rigidly secured thereto, said handle having an opening B' produced therein adjacent to its lower end, the metal being punched out and turned back, as shown at B², providing ears between which the projecting portion C' of the cover C is pivoted, the pivot-bolt C² passing through said projection and through the ears B², as most clearly shown in Fig. 3.

A rod D is pivotally connected to the end of the projection C', the upper end of said rod being pivotally connected to the links E, which links in turn are pivotally connected to the lower ends of the levers F, which cross each other and are pivoted to the handle at F'. The pin D', which serves to pivotally connect the rod D and links E, works in a slot D², produced in the handle, and is formed with an eye D³, to which is attached the lower end of a coil-spring G, the upper end of said spring being fastened at the upper end of said slot, as most clearly shown in Figs. 1 and 2. The purpose of this spring is to normally hold the rod D up, thereby maintaining a constant pressure upon the end of the projection C', thereby holding the cover C firmly closed upon the top of the cup or dipper A. In order to secure a tighter joint between the cover and top of dipper, I produce a groove C³ in the inner face of the cover and arrange a packing-ring C⁴.

In order to provide against leakage at the rear end of the cup or dipper, I arrange an inwardly-projecting plate H, which is fastened to the rear side of the cup adjacent to its upper edge and extends the entire width of the handle. This plate H has a connecting-plate H', which closes the space between the plate and dipper, and thereby prevents liquid passing between the plate and dipper. The cover is formed with a reentrant groove C⁵, which also contains the packing C⁴, said reentrant groove connecting the upper edge of the plate H, as most clearly shown in Fig. 3. Supplemental springs I are also arranged to connect the lower portion of the handle to the rear end of the projection C', said springs aiding the spring G in holding the cover down upon the cup or dipper.

In operation when it is desired to use the dipper the handles F² of the levers F are brought close to the handle B of the dipper, such action serving to force the rod D downwardly, and as the rod D is forced downwardly the cover is necessarily raised or opened and the cup or dipper can then be filled to its full extent, thereby measuring the quantity to be emptied. As soon as the cup or dipper is filled the lever-handles are released, and the springs will immediately return the cover to its closed or normal position, and the dipper

can be carried to the point desired without danger of spilling the contents. When the dipper or cup is to be emptied, the lever-handles are again pressed, opening the cover, 5 and the milk can be poured therefrom the same as from an ordinary cup or dipper.

Having thus fully described my invention, what I claim as new, and desire to secure by Letters Patent, is—

- 10 1. A device of the kind described comprising a dipper or cup and a handle having an opening near its lower end, a cover having a projection extending through said opening and pivoted therein, and a spring-actuated rod connected to the projection and carried by the handle, and means for operating the spring-actuated rod, substantially as described.
- 15 2. A device of the kind described comprising a dipper and handle, said handle having an opening near the bottom, the cover having a rear projection extending through the opening and pivoted therein, the rod connect-
20 ed thereto, the spring-actuated levers piv-
25 oted upon the handle and pivotally connect-
ed to the said rod, substantially as described.

3. A device of the kind described, comprising a cup or dipper, a handle attached thereto, the pivoted cover having a groove provided with a packing-ring, said cover having a rearwardly-projecting extension, a rod attached to said extension, the cross-levers pivoted to the handle, the links for connecting the levers and rod, a spring attached to the said rod at its upper end, the opposite 30 end of said spring being connected to the handle and the supplemental springs attached at one end to the handle and at the other end to the rear extension adjacent to the lower end of the handle, substantially as described. 40

4. The combination with a cup or dipper, having a curved plate arranged upon the inside thereof, of a pivoted cover, having a groove, provided with a packing-ring adapted to fit upon the rim of the cup, said cover 45 also having a reentrant groove provided with a packing and adapted to fit the top of the curved plate.

FRANCIS JAMES KEIS.
